ALISTER E. SMITH, OF LAURENS, AND CLYDE C. SMITH AND JESSE A. LANDS, OF SPARTANBURG, SOUTH CAROLINA.

DOFFING AND DONNING MECHANISM.

Application filed July 13, 1926. Serial No. 122,142.

The object of this invention is to provide a simple mechanism for simultaneously removing all the filled bobbins and discharging them simultaneously into a suitable receptacle alongside the spinning-frame and also to place on the spindles simultaneously a fresh set of empty bobbins, as more fully hereinafter set forth.

In the drawings annexed—

10 Figs. 1 to 5, inclusive, illustrate one form of carrying out our invention.

In the drawings annexed, 10 designates the usual row of spindles mounted upon the machine-frame 11, affixed to the front side 15 of which are two or more guide bars 12 having grooves in their faces for the reception of sliding bars 13 forming parts of a frame which is vertically slidable in a plane in front of the row of spindles, the 20 remaining parts of this frame being the horizontal bar 14, vertical end-bars 15 and an intermediate horizontal tie-rod 16 which passes through eyes 17 on the upper ends of rods 18 adjustably mounted in lugs 25 19 carried by the aforesaid slide bars 13.

This frame may be raised and lowered by any suitable mechanism. We have shown a pair of bell-crank levers 20 whose upper ends are connected by a horizontal movable 30 rod 21 and which are attached to horizontal pivotal shafts 22, the downwardly-extending arms of these bell-cranks being provided with fingers 23 which lie under the lower ends of the rods 18. These bell-cranks are operated on their pivots 22 by means of a lever 24 pivotally mounted on one of the shafts 22 and having an arm 25 which carries a roller-pin 26 lying under one of the bell-crank arms. By working the 40 lever 24 back and forth, the frame may be raised and lowered, and, in order to render this movement easy, we counterbalance the frame and connected parts by attaching a counterbalance 27 to one of the shafts 22.

45 On the aforesaid vertically-movable frame, we mount both the filled-bobbin doffers and the empty-bobbin donners. The empty-bobbin donning mechanism consists of a series of tubes 28, one for each spindle 50 10, these being rigidly affixed to a horizontal bar 29 whose ends are affixed to angle-arms 30 whose upper ends are pivotally attached to the vertical end-bars 15 at 31, the arrangement being such that, when the vertically-movable frame is raised to a pre-

determined point (as shown in Fig. 2), the tubular holders 28 will lie directly above the spindles when the series of tubes 28 are swung upwardly and inwardly toward the spindles, as shown in the aforesaid Fig. 2, 60 stops 32 being provided on the aforesaid movable frame to insure the exact positioning of the tubes 28. The empty bobbins are placed in the tubes 28 in an inverted position, being supported, points 65 down, by a closure spring 33 associated with each one of the tubes 28, so that, when this tube-carrying-frame is inverted, as shown in Fig. 2, the butt-ends of the bobbins will point downwardly and the bobbins, as 70 stated, be in a position to drop directly on the spindles when they are released. Each one of the tubes 28 is closed at its upper end by a gate 34, these gates being all attached to a horizontal bar 35 hinged to 75 the upper ends of the tubes 28, so that they may all be opened simultaneously to drop the empty bobbins on the spindles. Springs 36 are used to hold these gates normally closed, small handles or fingers 36' being 80 provided for conveniently swinging the hinged bar 35.

The filled-bobbin removing devices consist of pairs of grip loops 37 projecting outwardly from a pair of parallel bars 38 85 connected together at their ends by short upright pieces 39, the frame thus constructed being pivotally hung on the aforescribed rods 16 by means of arms 40. These parts are so proportioned that, when the 90 slidable frame is adjusted to a predetermined point with reference to the spindles, it may be swung upwardly and inwardly so as to bring the pairs of loops 37 directly in vertical alinement with the filled bobbins; 95 then, by lowering the slidable frame on the ways 12, the loops 37 will slide down over the respective filled bobbins. A gripper 41 is provided for each pair of loops 37, these grippers being mounted on a rod 42 journaled on the end-bars 39 and provided with handles 43 for rocking it to release the grippers simultaneously. A suitable number of coil-springs 44 is provided for holding the grippers in gripping position. When the 105 loops 37 are lowered onto the filled bobbins, the grippers 41 normally bite into the arm, without injuring the same, so that, when the loops 37 are raised through the medium of the slidable frame, the filled bobbins will 110

come off the spindles; and then, by swinging the gripper frame over outwardly, the series of filled bobbins may be carried out of the way of the empty-bobbin placing mechanism. It is desirable that, until the empty bobbins are placed on the spindles, the swinging frame carrying the just-removed filled bobbins shall be prevented from assuming its normal pendent position. To thus hold the filled bobbins suspended temporarily, we provide a pair of hooks 45 (as shown particularly in dotted lines at the top of Fig. 2). When the doffing is completed by the dropping of the empty bobbins, the hooks 45 are actuated to release the filled-bobbin carrier, thus permitting it to swing downwardly to normal position, with the points of the bobbins downwardly, the tube-carrying frame is swung outwardly and permitted to assume its normal inverted position, and then the slideable frame is lowered to bring the filled bobbins and empty tubes to a point considerably below the row of spindles, where they will not only be out of the way of the loom-attendant, but will be in convenient position for removing the filled bobbins and also for filling the tubes with empty bobbins (as shown in dotted lines at the lower part of Fig. 2).

To relieve the operator of manually holding up the frame when it is adjusted to doffing and donning position, any suitable holding device may be employed; as one means for this, we have shown a notched segment 50 which is adapted to engage a pawl 51, said segment being supported on the bearing 52 of the adjacent shaft 20 and

the pawl being provided with a chain 53 for convenience in releasing the pawl.

What we claim as new is:

1. In combination with a spinning machine, a support mounted in front of the row of spindles of the spinning machine, a rockable frame pivotally mounted on said support on an axis parallel to the row of spindles, this rockable frame carrying holders for the empty bobbins adapted to hold the bobbins in an inverted position when said rockable frame is swung outwardly away from the vertical plane of the spindles, the pivotal axis of said rockable frame being so positioned that when said rockable frame is swung over inwardly to thus invert the empty bobbins, said empty bobbins will lie in a position to be deposited on the spindles of the spinning machine.

2. In a machine of the class set forth, a spinning machine having a row of spindles, a vertically-movable frame and means for raising and lowering it, said frame being located in a plane adjacent to the spindles and being adapted to be lowered to a position below the same, said frame carrying doffing and donning mechanisms, the doffing mechanism consisting of an invertible supplemental frame pivoted on said slideable frame and carrying bobbin-grippers, and the donning mechanism consisting of an invertible frame pivotally mounted on said slideable frame and carrying donning holders.

In testimony whereof we hereunto affix our signatures this 28th day of June, 1926.
